SANTOS PASTOR, OF NEW YORK, N. Y.

AUTOMATIC DIAL DEVICE.

Application filed February 28, 1924. Serial No. 695,357.

The present invention relates to new and useful improvements in telephony, and it pertains more particularly to telephone systems of the automatic type.

- 8 In telephone systems of the above-mentioned type, sub-stations are called by means of impulses sent over the line by a manually-operated sender. The impulses are sent out in groups and each group requires a manual 10 operation on the part of the party operating the sender. The manual operation mentioned is tedious and time-consuming, and requires close attention on the part of the caller to avoid mistakes.
- 15 In systems of this character, it often happens that a party will have occasion to call the same line several times during the course of a day, and considerable time is thus consumed in carrying out the manual operations 20 necessary to make the several calls.

It is one of the primary objects of the present invention to combine with such a system means whereby a predetermined line may be called with but a single manual operation as 25 distinguished from a manual operation for each group of signals in the ordinary automatic system.

It is a further object of the present invention to combine a mechanical mechanism for 30 automatically sending a plurality of signal impulses over a telephone line with the conventional sub-station mechanism, without in any way interfering with the normal operation thereof.

35 It is a further object of the invention to provide means whereby either of a plurality of such sub-stations may be selectively called.

It is a further object of the invention to provide means of the above mentioned character which is capable of attachment to a 40 dial-operated or controlled sub-station without changing the internal construction thereof.

It is a further object of the invention to 45 provide means of the above-described character that will permit of the sub-station receiving incoming calls and making calls by means of the dial mechanism and in the ordinary manner.

50 It is a further object of the invention to construct the mechanism in such a manner that after a manual operation thereof, the same will return automatically to normal position.

55 The invention consists broadly of manually operated means preferably mechanical,

adapted for attachment to a telephone sub-station apparatus of the dial-operated type. The mechanism serves to send out a plurality of call signals in the form of impulses without in any way interfering with the normal 60 operation of the sub-station apparatus.

With the above and other objects in view, reference is had to the accompanying drawings, in which—

65 Figure 1 is a vertical sectional view of an apparatus constructed in accordance with the present invention, taken on the line 1—1 of Fig. 2;

Fig. 2 is a longitudinal sectional view 70 taken on the line 2—2 of Fig. 1;

Fig. 3 is a detail view partly in elevation and partly in section showing the impulse 75 sender in operation;

Fig. 4 is a horizontal sectional view taken 80 on the line 4—4 of Fig. 1;

Fig. 5 is a detail perspective view on an enlarged scale, showing the manner in which the impulse sending mechanism is operated;

Fig. 6 is a detail view showing the manner 85 of operation of certain contacts employed in connection with the device, the contacts being shown in closed position;

Fig. 7 is a similar view showing the contacts in open position;

Fig. 8 is a detail view in elevation of a portion of the mechanism;

Fig. 9 is a diagrammatic view of the circuit 90 employed in connection with the mechanically-operated device.

Referring more particularly to the drawings, the device comprises a cabinet 10 of any desired shape, and extending longitudinally of such cabinet on the interior thereof and mounted in suitable supports 11, there 95 is a shaft 12. Carried by this shaft 12 in spaced relation to one another, there is a plurality of impulse-sending-mechanism-operating elements. In the present instance there are three of these devices and they are 100 designated by the reference characters A, B and C. While in the present instance there are three of these devices shown, it is obvious that more or less as desired may be employed without departing from the spirit 105 of the invention. The impulse-sending-mechanism-operating element A is the master operating element, and it comprises a plurality of disk-like members 13 arranged in spaced parallel relation and each of these members 13 is connected with its next adjacent member by an angularly-disposed sec- 110

tion or portion 14. This construction makes the peripheral edge of the several members 13 continuous, and such construction in the master impulse-sending-mechanism-operating element is desired for a reason to be hereinafter more clearly set forth. The extreme right-hand member 13 is provided with an angularly-disposed lug or wing 14', while the extreme left-hand member 13 is 10 provided with an angularly-disposed lug or wing 15, the purpose of which will be hereinafter more fully described.

Each of the other impulse-sending-mechanism-operating elements comprises a plurality of disks suitably secured together in spaced parallel relation, there being, however, no connection between the disks in these impulse-sending-mechanism-operating elements as in the master impulse-sending-mechanism-operating element, and hence in this respect they differ from the master impulse-sending-mechanism-operating element. The disks of each of the impulse-sending-mechanism-operating elements are provided 25 on their peripheral edge with a plurality of projecting lugs or the like, 18', the purpose of which will be hereinafter more fully set forth.

Keyed or otherwise secured to the shaft 12, adjacent each of the impulse-sending-mechanism-operating elements, there is a gear, and such gears are designated by the reference characters A', B' and C'. Meshing with these gears A', B' and C', there are gears D', E' and F', respectively, and these gears D', E' and F' are each supported in a bracket 16 as more clearly shown in Fig. 4. Carried by the gears D', E' and F', there are small gears G', H' and J', respectively, and these small gears when rotated are adapted to drive their respective larger gears D', E' and F'. These small gears G', H' and J' are driven by means of reciprocating racks K', L' and M', respectively, and these racks are carried by the lower end of the keys 17, 18 and 19, respectively. Each of these keys is reciprocatingly mounted in a suitable bushing 20 in the top wall of the cabinet, and surrounding each 50 of the keys there is a spring 21 which serves to maintain the key in normal extended position.

Secured at one end to the shaft 12 and at the other end to a pin 22 carried by one end 55 of the cabinet, there is a spring 23, and said spring serves to return the shaft 12 to normal position after an operation thereof by the depression of one of the keys 17, 18 and 19.

Extending longitudinally of the cabinet there is a suitable support 24, and mounted upon the upper face of the support there is a guide or channel member 25. Slidably mounted in this guide or channel member 25, there is a strip 26 and said strip 26 car-

ries a plurality of bearing blocks or the like, 27, 28 and 29. By this construction when the strip 26 is reciprocated or moved in the guide 25, all of the bearing blocks 27, 28 and 29 will be moved simultaneously. 70 Pivotaly mounted in each of the blocks 27, 28 and 29, as at 30, there is a rocking lever 31, having a forward extension 32 and a downwardly extending arm 33. Projecting forwardly from the block 27, there is a 75 forked member 34, and said forked member is adapted to receive one of the members 14 of the master impulse-sending-mechanism-operating member A. By this construction, as the master impulse-sending-mechanism-operating member A is rotated the block 27 and the strip 26 will be moved longitudinally of the guide 25, which mechanism serves to simultaneously move the blocks 27, 28 and 29. As this forked member engages 80 either of the angularly disposed lugs or ears 14' or 15, the sliding movement of the strip 26 is stopped, as is also the rotary movement of the master impulse-sending-mechanism-operating member A. 85

Mounted upon the support 24, there is a plurality of impulse senders designated by the reference characters X, Y and Z. All of these impulse sending mechanisms are of the same construction, and the description of one therefore will suffice. Referring to Fig. 5, it will be noted that these impulse-sending mechanisms comprise a plurality of blocks 40 of suitable insulating material, which blocks are secured together by means of screws or the like, 41. Secured between these blocks 41, there is a T-shaped member 42, and carried by the lower end of each of the T-shaped members 42, there is a binding post 43 to which is connected a conductor. Mounted on one of the blocks there is a contact 44 having a contact point 45, and carried by each of these contacts 44 there is a binding post 46 to which is connected a suitable conductor. 100

By reference to Fig. 1, it will be noted that each of the keys 17, 18 and 19 is provided with a cam member 60 intermediate its ends. Mounted adjacent each of these cam members there is a reciprocating member 61, having a roller 62 adapted to be engaged by the cam member to reciprocate its respective member 61. Each of these reciprocating members is adapted to control contacts, which contacts are designated by the reference characters N, O and P in Fig. 9. As shown in Fig. 6, these contacts are closed when the keys are in their normal position, but when the keys are depressed the contacts are broken as shown in Fig. 7. 110

The operation of each of the keys and the impulse-sending-mechanism-operating elements being the same, it is necessary to describe the operation of one only, and in 115 120 125 130

this description the operation of the key 17 and the master impulse-sending-mechanism-operating element will be described in detail.

5 Referring to Fig. 9, the reference character R designates the sub-station apparatus including a dial device D in the signal circuit of the system, the impulse senders being designated by the reference characters 10 X, Y and Z, which are connected in the signal circuit through the device D, and the contacts in the cabinet being designated by the reference characters N, O and P as heretofore described.

15 With the parts in the position shown in the drawings, if the key 17 be depressed, through the medium of the rack bar K' the gear G' will be rotated. This gear serves to rotate the gear D', and through the me-

20 dium of the gear A' the shaft 12 will be rotated and the spring 23 placed under tension. As the shaft 12 is rotated, through the medium of the forked member 34 the strip 26 and the parts carried thereby will

25 be moved from the position shown in Fig. 2, that is, to the right of the master impulse-sending-mechanism-operating element A, to the position shown in Fig. 5 to the extreme left of the master impulse-sending-mech-

30 aism-operating element A and into engagement with the stop 15. As this key 17 is

35 depressed, the cam face 60 thereof will engage its respective reciprocating member 61 and move the resilient contact members of the contacts N to the dotted-line position shown in Fig. 9. If, now, pressure on the key 17 be released, under the influence of the spring 23 the shaft 12 will be rotated in the opposite direction to that in which

40 it is rotated by the rack K', and as it rotates in this direction the lugs 13' of the several disks of the master impulse-sending-mechanism-operating element will engage the forward extension 32 of its respective

45 lever 31, rocking the lever about its pivotal point 30, and through the medium of the end 33, make and break the circuits at the contacts 44, which is designated at "X" in Fig. 9. As each of the lugs 13' engages the

50 forward extension 32 of the lever 31, one impulse is sent out and the series of impulses depends upon the number of lugs 13' on the peripheral edge of the impulse-sending-mechanism-operating element A.

55 By employing a plurality of impulse-sending-mechanism-operating elements and arranging the lugs on the periphery of the disks at different intervals, the impulse signals sent out may be arranged in various

60 combinations, and, consequently, call lines may be called by a single manual operation, that is, the depression of one of the keys 17, 18 and 19, dependent upon the line desired.

65 Take, for example, the operation just described: When the contacts N are broken,

upon the operation of the impulse sender X the impulses will be sent out. Simultaneously with this operation, the impulse senders Y and Z will be operated, but owing to the fact that the contacts O and P are in engagement with each other, the circuit controlled by the impulse senders Y and Z will not be broken, and, consequently, these impulses will not be sent over the line. In order to send impulses by the impulse senders 70 Y and Z, it is necessary to depress the key 18 of the impulse-sending-mechanism-operating element B or the key 19 of the impulse-sending-mechanism-operating element C, since these keys upon their depression operate to open the contacts O and P, respectively, so that their circuit may be interrupted by the impulse senders Y and Z dependent upon the key depressed.

75 From the foregoing it is apparent that the present invention provides a mechanical mechanism which upon a single manual operation, i. e., that of depressing a key, will call a certain station without requiring a dial operation on the part of the caller, and 80 by elimination of the dial operation, considerable time in the operation of a telephone sub-station for the purpose of calling a called station is reduced.

85 What is claimed is:

1. In a telephone system, a plurality of branch circuits connected in parallel with the signal circuit of the system, an impulse sending mechanism associated with each of said branch circuits for optionally sending 100 different impulse signals over the signal circuit, and means for selectively operating the impulse sending mechanisms to send any one of the different impulse signals over any one of the branch circuits as the result of a single manipulation.

105 2. In a telephone system, a plurality of branch circuits connected in parallel with the signal circuit of the system, an impulse sending mechanism associated with each of said branch circuits for optionally sending different impulse signals over the signal circuit, means for selectively operating the impulse sending mechanisms to send any one of the different impulse signals over any one 110 of the branch circuits as the result of a single manipulation, and means associated with each branch circuit serving to render the impulse sending mechanisms of the non-selected branch circuits inoperative as impulse senders.

115 3. In a telephone system, a plurality of branch circuits connected in parallel with the signal circuit of the system, an impulse sending mechanism associated with each of said branch circuits for optionally sending different impulse signals over the signal circuit, means for selectively operating the impulse sending mechanisms to send any one of the different impulse signals over any one 120 of the branch circuits as the result of a single manipulation, and means associated with each branch circuit serving to render the impulse sending mechanisms of the non-selected branch circuits inoperative as impulse senders.

of the branch circuits as the result of a single manipulation, means for simultaneously operating said impulse sending mechanisms, and means for rendering certain of said impulse sending mechanisms inoperative.

4. In a telephone system, a plurality of branch circuits, connected in parallel with the signal circuit of said system, a plurality of impulse sending mechanisms associated respectively with said branch circuits, said impulse sending mechanisms operable for sending a predetermined impulse signal over the branch circuits respectively to the signal circuit by a single operation, each of said mechanisms including cam-operated means for normally closing its related branch circuit, and operable to open said branch circuit to permit the sending of an impulse signal, and means for actuating said cam-operated means to close the related branch circuit subsequent to the impulse signal-sending operation.

5. In a telephone system, a plurality of branch circuits, connected in parallel with the signal circuit of said system, a plurality of impulse sending mechanisms associated respectively with said branch circuits, said impulse sending mechanisms operable for sending a predetermined impulse signal over the branch circuits respectively to the signal circuit by a single operation, each of said mechanisms including cam-operated means for normally closing its related circuit and operable to open said circuit to permit the sending of an impulse signal, and spring-actuated means for actuating said cam-operated means to close the related circuit subsequent to the impulse signal-sending operation.

6. In a telephone system, a plurality of branch circuits, connected in parallel with the signal circuit of said system, a plurality of impulse sending mechanisms associated respectively with said branch circuits, said impulse sending mechanisms operable for

sending a predetermined impulse signal over the branch circuits respectively to the signal circuit by a single operation, each of said mechanisms comprising circuit make-and-break devices, a cam associated with one of said make-and-break devices, an impulse element associated with the other of said make-and-break devices, gearing connected to said impulse element, a spring actuated key, said cam being carried by said key, and a gear rack carried by said key which cooperates with said gearing, the movement of said key causing the operation of one of said make-and-break devices to first open the related branch circuit to permit the sending of an impulse signal, and to subsequently close the branch circuit upon the return movement of said key.

7. In a telephone system, manually operated mechanism for sending a predetermined impulse signal over a signal circuit of said system by a single operation of said mechanism, said mechanism comprising a cam operated means for normally closing said circuit and operable to open said circuit to permit the sending of the impulse signal, a spiral impulse element mounted for rotation and having projections on the peripheral edge thereof, a make and break device in said circuit operated by the projections when said impulse element rotates in a signaling direction, means for rotating said impulse element in a non-signaling direction, means operable for rotating said impulse element in a signaling direction to cause the projections thereon to actuate said make and break device to send a predetermined impulse signal over said circuit, and means which coacts with portions of said impulse element causing said make and break device to travel in response to the movement of said impulse element whereby to be acted on by a predetermined number of said projections.
